UNITED STATES PATENT OFFICE.

KERFOOT A. AFFLECK, OF WASHINGTON, DISTRICT OF COLUMBIA.

TRUNDLING TOY.

Application filed May 26, 1921. Serial No. 472,663.

To all whom it may concern:

Be it known that I, KERFOOT A. AFFLECK, a citizen of the United States, residing at Washington, in the District of Columbia, 5 have invented certain new and useful Improvements in Trundling Toys, of which the following is a specification.

The invention has for an object to effect improvements in trundle toys of that type 10 in which a wheel is connected to the end of a propelling rod, and a figure mounted slidably upon the rod connected eccentrically to the wheel. It is an important aim of the invention to effect improvements in means 15 for introducing new elements of action in movement of a figure, whereby a closer simulation of the natural galloping and other movements will be attained. It is an advantage of this that a movement may be 20 produced in the figure which will produce a sound closely resembling that of a galloping animal, and part of the figure may intermittently engage the ground without its action becoming blocked, and without requiring an 25 accurate positioning of the propelling rod. It is also an aim to simplify the construction of such device enabling its production and sale at a low cost.

Additional objects, advantages and features of invention reside in the combination, 30 arrangement and structure of parts which will be understood from the following description and drawings, wherein,

Figure 1 is an elevational view of the device constructed in accordance with my invention,

Fig. 2 is a top view thereof,

Fig. 3 is a rear view,

Fig. 4 is a section on the line 4—4 of 40 Fig. 1 illustrating the relative proportions of the pusher rod and the guiding part.

There is illustrated a trundling toy comprising a disk wheel 10, mounted revolvably upon the end of a pushing rod or handle 11, 45 the wheel 10 having a screw 12 engaged tightly therein, the outer part of which is revolvably in the end of the rod 11. The degree of eccentricity in the location of this bearing may be varied to suit the requirements of various toys or the need for the action desired. A washer 13 is interposed between the end of the rod 11 and the wheel 10. The rod is shown as made in two sections, the outer part 11' being connected to the inner part by a scarf joint at 14. This 50 enables the device to be packed in a small

compass for shipment, and also enables the use of miscellaneous stock lengths of material, reducing the cost of production correspondingly.

The figure 16 associated with the parts described in the present instance is that of a dog, which may be cut out of suitable stock board or other material in the form and size desired. The body of the figure is 60 formed with extended limbs resembling those of a galloping animal, and the extended front paw portion 17 is connected to a suitable wrist 18 on the side of the disk 10 opposite to the rod 11, and the wrist may be 65 similar to the mounting of the rod 11 upon the wheel, a washer 19 being interposed between the leg piece 17 and the wheel 10. A guide block 20 is mounted upon the side of the figure next the rod 11, the block being 70 formed of a section of ordinary planking, one edge secured against the side of the figure 16 with the block at right angles to the mean position of the rod 11 when the device is being propelled, the block being of a size 75 and having its outer edge portion recessed so as to receive the rod 11 therein for relative vertical oscillation. The rod 11 is confined in the recess by a strap piece 21 secured 80 across the recess, forming a slot 22. The 85 slot is ordinarily made of a size to engage snugly, but without undue friction, the sides of the rod 11, but is considerably elongated in a vertical direction. The parts are so proportioned and assembled that when the 90 figure and wheel are in the position shown in Fig. 1, and the rod held as it would naturally be held by children of such ages that they would use the toy, there will be a space in the slot 22 above the rod, so that the figure 95 will be free to rest upon the ground at times, even should the rod be raised slightly from time to time, as might happen by reason of inequalities of pavement surfaces, or other causes.

In the use of the device, when it is propelled in a forward direction with the rod 11 held as indicated, starting with the parts in the position illustrated in solid lines in Fig. 1, the eccentricity of the pivoting of the rod 11 upon the wheel 10 will cause the rod to rise, engaging against the upper end of the slot and lifting the figure at the rear part, the wrist 18 in the meantime moving rearwardly and then upwardly so that the figure 105 is caused to ride bodily in a manner very 110 much like that of the body of a dog after

a leap. As the wrist 18 passes over the upper range of movement, the eccentric connection 12 is moving downwardly, and permits the rear part of the figure to fall rapidly and to engage the ground as the wrist 18 moves downwardly, but the rear end falling more rapidly than the forward end. The movement of the guide 20 forwardly and downwardly on the rod also causes rapid lowering 5 of the rear part of the figure, so that with the guide properly positioned, the rear of the figure will engage the ground even without the eccentric connection of the rod to the wheel. This eccentric connection of the 10 rod to the wheel, however, is preferred in order to add a further desirable quality to the action of the figure in movement. The forward progress of the figure 16 relatively to the ground surface becomes very much 15 slowed at this period in the action of the device, and the parts soon regain the position shown in Fig. 1, when the action described is repeated. In the even progression of the wheel 10, however, the retardation of forward 20 movement of the figure is not detrimentally notable, and the resultant effect is a close simulation of a true galloping action. It should be noted that by reason of the eccentric connection of the push rod to the 25 wheel, the small radius between the pivot connection and the ground, and the large radius between the ground and the wrist 18 will result in a very much accelerated and abruptly forward movement of the figure 30 immediately after the parts pass the position shown in Fig. 1, thus closely simulating the spring of an animal.

At the same time, when the device is being 35 operated, the engagement of the rod 11 with the upper part of the slot 22 for lifting of the figure, and the rapid lift and forward throwing movement of the figure results in the rod being rapidly engaged by the upper and lower edges of the slots 22, the figure 40 being thrown upwardly some extent and forwardly.

The device has operated satisfactorily in use, and it will be evident that it is adapted to manufacture at a minimum of cost and 45 labor.

It is to be noted that the rod 11 and the connection of the figure with the wheel in the present instance are both in a direction closely adjacent the same radius of the axis of the wheel, with the connection of the 55 rod 11 slightly in advance of the radius to the wrist 18.

What is claimed:—

1. A device of the character described comprising a wheel element, a push rod element connected eccentrically to the wheel, a figure element having a part pivoted upon the wheel, the figure having a guide member formed with a slot receiving the rod and having a vertical dimension much greater than the corresponding measurement of the engaged part of the rod, to permit loose vertical movement of the figure relatively to the rod, the guide member being at such height on the figure that a part of the figure 60 may rest upon the ground for periods intermittently during operation of the device. 65

2. A device of the character described comprising a wheel, a rod element pivoted upon the wheel, a figure element pivoted eccentrically on the wheel and having a lateral block secured thereto having a vertical slot therein to receive the rod element and much larger than the transverse dimension of the rod, for loose vertical movement a suitable 70 distance, the block being located so as to permit trailing of the figure upon the ground at certain stages of operation, and to rest 75 slidably upon the rod element at other times, for support of the figure element. 80

3. A device of the character described, comprising a wheel, a rod element pivoted upon the wheel, a figure element pivoted eccentrically on the wheel, said figure being also mounted on the rod medially of the 90 figure, said mounting including means 95 slideable on the rod and also constructed for limited loose vertical movement of the figure relatively to the rod and positioned for trailing of the figure upon the ground intermittently.

In testimony whereof I have affixed my signature.

KERFOOT A. AFFLECK.
